UNITED STATES PATENT OFFICE.

LONZO J. COOPER, OF KENNEDY, OHIO, ASSIGNOR TO AMERICAN LAUNDRY MACHINERY COMPANY, OF NORWOOD, OHIO, A CORPORATION.

SHIRT-IRONING TABLE.

SPECIFICATION forming part of Letters Patent No. 766,222, dated August 2, 1904.

Application filed December 17, 1903. Serial No. 185,600. (No model.)

To all whom it may concern:

Be it known that I, LONZO J. COOPER, a citizen of the United States, residing at Kennedy, in the county of Hamilton and State of Ohio, 5 have invented certain new and useful Improvements in Shirt-Ironing Tables, of which the following is a specification.

My invention relates to the ironing-table of a shirt-ironing machine, the object being to 10 simplify the clamping and supporting mechanisms for holding the pad and the shirt on the table.

The features of my invention are more fully set forth in the description of the accompanying drawings, forming a part of this specification, in which—

Figure 1 is a top plan view of my improved shirt-table and clamp. Fig. 2 is a side elevation of a portion thereof. Fig. 3 is an enlarged end elevation of the neck-pad clamp. Fig. 4 is a section on line *xx*, Fig. 3. Fig. 5 is an enlarged side elevation, partly in section, of the clamping mechanism. Fig. 6 is a section on line *ww*, Fig. 5. Fig. 7 is a section on line *vv*, Fig. 5. Fig. 8 is a detailed sectional view of the clamping-spring. Fig. 9 is a section on line *ww*, Fig. 4.

This table is particularly adapted and designed to be used on a shirt-ironing machine, 30 constituting a separate invention, on which I am applying for an independent patent of even date herewith—to wit, application on an ironing-machine, filed December 17, 1903, Serial No. 185,599. The feature of the said ironing- 35 machine, so far as it concerns the construction of the ironing-table of this application, consists in a plurality of ironing-tables seated on a common rotatable support, each table being adapted to be independently reciprocated 40 vertically upon its supporting-seat. However, many of the features shown and described in this application relate to an ironing-table generally, irrespective of the machine upon which it is to be used.

Looking at Fig. 2, 1 represents the supporting base-plate, provided with vertical depending stems 2, by means of which this table is attached to its support and which constitute

guides permitting of a vertical reciprocation of this table on its support. 50

3 represents a column elevated from the base-plate 1, through which column passes the supporting and adjusting shaft 4, the upper end of which is screw-threaded.

6 represents a ring fixed to the shaft 4 for 55 turning the same and provided with wrench-holes 7.

8 represents the ironing-table proper, which is provided with depending column 9, corresponding with the supporting-column 3. Column 9 is provided with a bore screw-threaded to engage the screw-threaded end of the shaft 4. 60

10 represents a dowel-pin projected from the column 3 and engaging into a corresponding bore in column 9 for giving accuracy of movement of the table 8 relative toward base-plate 1. It is obvious that by turning the ring 6 the distance between the table 8 and plate 1 may be delicately adjusted. 65

11 represents the neckband erected at one end of the ironing-table. The neckband-plate 11 is a separate piece from the table, adapted to be raised therefrom, so that the covering-pad 12 may be inserted under the neckband 75 11, thus exposing the entire surface of the ironing-table clear up to the outside face of the neckband 11 to the action of the iron. Obviously this enables the entire shirt-bosom to be ironed in one operation. This plate 11 is mounted upon a pin 13, which pin projects through a hole in the face of the table, as shown in Figs. 9 and 4. 80

14 represents a spring one end of which is secured to the table 8, the other end to the 85 pin 13, said spring normally exerting a downward strain on pin 13, and consequently on the neckband 11. The under side of said plate 11 is provided with teeth for engaging into the covering-pad 12. 90

16 represents a bracket dependent from the rear of the neckband 11 and engaging into a slot in the rear of the ironing-table, as shown in Figs. 3 and 4. Obviously by lifting up pin 13 the neckband 11 may be raised from 95 the table for removal or insertion of the pad.

This is a very simple way of holding the pad, affording great convenience for removal and insertion.

17 represents the band which goes around 5 the edge of table 8 for holding the pad in position. The shirt is slipped over this table.

I will now describe the mechanism for clamping the neckband of the shirt against the neckband-plate 11 and the shoulders of 10 the shirt against band 17.

Base 1 is provided at one end with a bracket 18, having a pivot-bolt 19, upon which are fulcrumed the neck and shoulder clamps.

20 represents a lever fulcrumed on bolt 19. 15 The upper end of said lever 20 has a journal-bracket 21. Fulcrumed in said bracket is a journal-pin 22. Said journal-pin 22 carries an eccentric 23, having an operating-handle 24. Fulcrumed to the said eccentric is a neckband-clamp casing 25. The neckband-plate 20 consists of a plate 26, adapted to fit the neckband plate 11. Plate 26 has an orifice 27, adapted to engage over the locking-lug 28 of the neckband-plate 11. The plate 26 has an 25 arm 29 extended into a casing 25.

31 (see Fig. 8) represents a coiled spring interposed between and connecting the arm 29 to the inside of the casing 25.

32 represents an adjusting-nut upon the end 30 of the arm 29 for adjusting the tension of the spring 31. The casing 25 has a lug 33, and it is this lug 33 which is fulcrumed to the eccentric 23. Thus the neck-clamp as an entirety can swing on the eccentric 23, to which 35 it is fulcrumed, toward and from the neckband-plate 11, and at the same time eccentric 23 may be turned on its pivot 22 in the bracket 21, so as to swing eccentric 23 and its entire neck-clamp to and from the neckband-plate 11. 40 Obviously 11 represents the stationary, and 26 the movable jaw member of the neckband-clamp.

34 represents a shoulder-clamp fulcrumed 45 on the bolt 19 at points outside of the lever 20. The upper end of the said lever 34 is provided with shoulder-clamps 35, adapted to clamp each shoulder of the shirt against the band 17. The intermediate portion of the lever 20 is cut out at 36, and in the said cut-out portion is fulcrumed the eccentric-lever 50 clamp 37, the cam portion of the said eccentric being adapted to project through the cut-out portion 36 of the lever 20 and to engage against the shoulder-clamping lever 34.

55 A shirt being in position, the shoulder-clamping lever 34 is swung over against the band 17. The lever 20 is swung over against the shoulder-clamping lever 34. The neck-clamp casing 25 is swung on its pivot on the eccentric 23 until the plate 26 engages the stationary neck-plate 11. The operating-handle 24 is now swung down, which turns the eccentric 23 on its pivot, which movement compresses the spring 31, pulling the arm 29 60 outward, and so establishing a clamping relation between the plates 26 and 11. The lever 20 is by this movement held firmly against the shoulder-clamping lever 34; but as yet the clamps 35 have not been compressed against the band 17, levers 20 and 34 being in contact 70 and the eccentric lever 37 being depressed, as shown in Fig. 5. The cam 38 is contained within the cut-out portion 36 of lever 20. When the lever 37 is swung up, the cam 38 is projected from the lever 20 and against the 75 abutment of the lever 34, thus exerting additional strain on the spring 31, and so forcing over the clamps 35 against the shirt-shoulders stretched over the band 17. In this position the operating-lever 37, being swung up, is 80 crossed over the other operating-handle 24, which is swung down, and to release both clamps all that need be done is to swing up the lever-handle 24, thus releasing all the tension on the spring 31, and so dropping the 85 lever 37 again, and thus simultaneously disengaging both the shoulder and the neck clamps.

Various ways of altering the specific shape 90 of the lever and clamps may be devised without departing materially from the functions of these parts. With my arrangement spring 31 effects both clamping operations of neck and shoulder, enabling a simultaneous release of both clamps by the manipulation of one of 95 the levers.

This device is very simple in operation, and its convenience and facility of operation materially decrease the time required in inserting and removing a shirt from the ironing-table. 100

Having described my invention, I claim—

1. In combination with an ironing-table, a neckband-plate, a clamp therefor, a lever, a spring-controlled connection between said lever and clamp, and an eccentric for straining 105 said clamp, between the lever and the neckband-plate, substantially as described.

2. In combination with a shirt-ironing table, a neckband-plate, a lever, carrying shoulder-clamps, a second lever outside of said shoulder-clamp lever, a neckband-clamp, having spring-controlled connection with said second lever and controlling means whereby the said spring strains both shoulder and neck clamps, substantially as described. 110

3. In combination with a shirt-ironing table, a neckband-plate thereon, a lever carrying shoulder-clamps, a second lever outside of said shoulder-clamp lever, a neckband-clamp having spring-controlled connections with 120 said second lever, a handle for said neckband-clamp, and a second handle fulcrumed on said second lever, and having one end engaging against the outside of the shoulder-clamp lever, substantially as described. 125

4. In combination with a shirt-ironing table, a neckband-plate, a lever carrying shoulder-clamps, a second lever adapted to engage the first lever, in its movement toward the end of the ironing-table, an eccentric lever 130

- fulcrumed in the end of said second lever, a spring-controlled neckband-clamp fulcrumed on said eccentric lever, and a second eccentric lever fulcrumed on said second lever, and 5 adapted to engage the outside of the shoulder-clamp lever, substantially as described.
5. In combination with an ironing-table, a neckband-plate, a neckband-clamping compound lever, a shoulder-clamp lever between 10 the end of the ironing-table and said compound lever, a spring interposed between the neckband-clamp and said compound lever, a handle for engaging and disengaging said neckband-clamp with said plate and for straining said 15 spring, and a second lever fulcrumed on said compound lever and adapted to engage with the outside of the shoulder-clamp lever and imparts additional strain to said spring, substantially as described.
- 20 6. In combination with an ironing-table, a neckband-plate, a neck-clamping lever, a shoulder-clamping lever, between the end of the table and said first-named lever, a neckband-clamp having spring-controlled connection with the first-named lever, means on said first-named lever for engaging the neck-clamp with the neck-plate and straining said spring, and means on said first-named lever for engaging said shoulder-clamp lever and straining 25 the same toward the end of the table, while straining the first-named lever from the end of the table, thereby imparting additional clamping strain to said spring, substantially as described.
- 30 7. In combination with an ironing-table having a neckband-plate, a base-plate, a journal-bracket, a neck-clamping lever journaled in said bracket, a shoulder-clamping lever journaled in said bracket and movable between 35 said first-named lever and table, an eccentric lever fulcrumed in the end of said neck-clamp lever, a casing fulcrumed to said eccentric lever, a neck-clamp having an arm projecting into said casing, a spring connection between 40
- said casing and arm, and a second eccentric lever fulcrumed to said neck-clamping lever and adapted to control the shoulder-clamp lever, substantially as described.
8. In combination with an ironing-table, having a neckband-plate, a base-plate, a journal-bracket, a neck-clamping lever journaled in said bracket an eccentric lever fulcrumed in the end of said neck-clamping lever, a casing fulcrumed to said eccentric lever, a neckband-clamp having an arm projecting into said casing, a spring connecting said casing to said arm, and a handle for operating said eccentric lever, substantially as described.
9. In combination with an ironing-table, having a neckband-plate, a base-plate, a journal-bracket, a neck-clamping lever journaled in said bracket, an eccentric lever journaled in said neck-clamping lever, and a neck-clamp fulcrumed to and having a spring connection with the said second clamping-lever, substantially as described.
10. In combination with an ironing-table, having a neckband-plate, a journal-bracket, shoulder-clamping lever and a neck-clamping lever journaled in said bracket, the shoulder-clamping lever being intermediate of the table and the neck-clamping lever, an eccentric lever fulcrumed in the neck-clamp lever, a neck-clamp fulcrumed to and having spring-controlled connection with said eccentric, a second eccentric lever fulcrumed to the spring-clamping lever, adapted to transmit the tension of said spring to the shoulder-clamp, and handles for said eccentric levers whereby said clamps are simultaneously released, when the first-named eccentric lever is released, substantially as described.

In testimony whereof I have hereunto set my hand.

LONZO J. COOPER.
